 Eclipse Machine Company, Elmira, N. Y., a
 corporation of New York

Application December 21, 1931, Serial No. 582,413

6 Claims. (Cl. 123—179)

This invention relates to a starter control for internal combustion engines and more particularly to a device for controlling the actuation of a starting system from a manual control member for the engine, such actuation being also controlled by a disabling mechanism responsive to self-operation of the engine.

It is an object of the invention to provide a novel device for controlling an engine starter mechanism from a manual control element of the engine or transmission such as the accelerator pedal or clutch pedal, the controlling connection being broken responsive to self-operation of the engine.

Another object is to provide such a device in which the disruption of said connection is brought about by means of a fluid pressure generated by an auxiliary device such as a pump operated by the engine.

A further object is to provide such a device in which the fluid pressure so generated is prevented from breaking such connection during the cranking operation.

Another object is to provide such a device having provisions for preventing the reactuation of the starting mechanism for a predetermined time after self-operation of the engine has ceased.

Another object is to provide such a device in which the automatic controlling mechanism is operative in response to rotation of the engine in either direction.

Further objects and advantages will be apparent to those skilled in the art from the following description taken in connection with the accompanying drawings in which:—

Fig. 1 is a somewhat diagrammatic showing of a preferred embodiment of the invention, certain of the parts thereof being shown in vertical section;

Fig. 2 is a detail in side elevation of a second embodiment of the invention showing a modified form of controlling means;

Fig. 3 is an end view of the structure shown in Fig. 2;

Fig. 4 is a view similar to Fig. 1 of another embodiment of the invention; and

Fig. 5 is an elevation partly in section and partly diagrammatic of an internal combustion engine of commercial type with the embodiment of the invention illustrated in Fig. 4 applied thereto.

Referring to Fig. 1 of the drawings there is illustrated a starting system for an internal combustion engine including a battery 1 grounded at 2 and connected by a lead 3 to a starting switch

4 of a starting motor 5 which is grounded at 6 to complete the starting circuit.

A manual control member for the engine is illustrated in the form of an accelerator pedal 7 having a thrust link 8 with a collar 9 fixed thereon in position to engage a lever 10. Lever 10 is hinged at 11 and has pivoted to its free end a rod 12 arranged to operate the throttle of the engine carburetor, not shown.

According to the present invention, means are provided for connecting the accelerator pedal 7 to operate the starting switch 4 when the engine is not in operation. As here shown this connecting means comprises a sleeve member 13 arranged to slidably receive a cylindrical enlargement 14 of the push member 8, and pivoted at 15 to a switch operating lever 16. Lever 16 is hinged at 17 and carries at its free end an insulated roller 18 arranged to contact the movable member 19 of starting switch 4 to close the switch when the sleeve member 13 is moved by depression of the accelerator pedal.

The sleeve member 13 is normally connected to the push member 8 by means of a latch 21 slidably mounted in a cylinder 22 formed on the sleeve member 13 at right angles thereto, said latch normally extending into the path of shoulder 23 formed on the cylindrical enlargement 14. The latch 21 is formed as a piston fitting within the cylinder 22 whereby a vacuum formed in the upper end of said cylinder will trip the latch 21 and disable the connection between the accelerator pedal 7 and switch operating lever 16.

According to the present invention, means are provided for causing the disabling of said connection when the engine is self-operative. As illustrated in Fig. 1, this means comprises an air pump indicated generally at 24 which is preferably mounted directly on the frame 25 of the engine to be started. As here shown this pump 24 comprises a flexible diaphragm 26 arranged to be operated by a bell crank lever 27 which is urged in a direction to raise the diaphragm 26 by suitable means such as a spring 28, and which is positively operated to depress the diaphragm 26 by a thrust member 29 bearing on a cam 31 driven from a rotating part of the engine. Suitable check valves 32 and 33 are provided whereby reciprocation of the diaphragm 26 will cause air to be drawn in through the inlet 34 into chamber 35 and expelled through chamber 36 and outlet 37.

As here illustrated, the inlet 34 is connected by means of a flexible conduit 38 with the upper end of the cylinder 22 whereby operation of the

pump 24 causes a vacuum to be formed in said cylinder, withdrawing and maintaining the latch 21 in inoperative position. It will be noted that the pump 24 operates equally well whether the engine is rotating backward or forward so that self-operation of the engine in either direction will cause disabling of the connecting means between the accelerator pedal and starting switch.

Means are provided for preventing the disabling of said connection during the cranking operation. As shown in Fig. 1 this means comprises a valve 38 interposed in the conduit 38 and having a movable plunger 41 pivoted at 42 to the cylinder 22 of sleeve member 18, and with an opening 43 registering with the inlet and outlet ports of said valve when the sleeve member 18 is in its normal position. Motion of the sleeve member 18 in a direction to close the starting switch 4, however, causes the plunger 41 to slide through the valve 38 whereby the passage 43 is moved out of registry with the valve ports and the cylinder 22 is cut off from the vacuum produced by the pump 24. The latch 21 is therefore not affected by the pump 24 during the cranking operation, but when the engine starts and the sleeve member 18 is returned to its normal position as by means of a return spring 44, the valve 38 will be reopened and the latch 21 will be retained in its inoperative position as long as the engine is running.

Another embodiment of the invention showing a different method of preventing the pump 24 from affecting the latch 21 is illustrated in Figs. 2 and 3. In this embodiment of the invention, the cylinder 22 is continuously connected to the pump 24 but a port 45 is provided in the side of the cylinder 22 which port is normally closed by a starting switch lever 46 which is pivoted to the cylinder 22 at 47 in position to cover said port when the parts are in normal position. Motion of the sleeve member 18 in a direction to close the starting switch 4, however, causes the port 45 to be uncovered, whereby the vacuum created in the pump 24 is ineffective to raise the latch 21.

It will be understood that the air pump 24 may be used either as a vacuum pump or as a pressure pump if so desired. When used as a pressure pump it is merely necessary to connect the flexible conduit 38 to the outlet 37 instead of the inlet 34, and to form the latch 21 so as to be pushed away from the pump instead of toward the pump in moving to its inoperative position.

Means are provided for preventing the reestablishment of the connection between the accelerator pedal 1 and starting switch 4 until a predetermined time after the engine has come to rest. As illustrated in Fig. 1, this means comprises the chamber 35 of the pump which acts as a storage reservoir, and an adjustable bleeder valve 48 which is set to dissipate the vacuum in the chamber 35 a predetermined time after the pump has stopped.

In the embodiment of the invention illustrated in Figs. 4 and 5, the objects of the invention are secured by utilizing the lubricant pump of the engine to produce the pressure for causing the disabling of the starter connection during the self-operation of the engine. As there illustrated, the parts of the starting system and fuel control system of the engine are the same as shown in Fig. 1 and are similarly numbered. In this embodiment, however, a latch 49 is provided for connecting the sleeve member 18 to the push link 8 which latch is provided with a shoulder

51 normally held in the path of a reduced extension 52 on the push member as by means of a spring abutment 53. Latch 49 is provided with an opening 54 which is adapted to be moved into registry with the reduced extension 52 by a pressure responsive device in the form of an elastic bellows 55 mounted in the upper end of cylinder 56 formed on sleeve member 18, in position to bear on the latch 49.

The bellows 55 is connected to the lubricant pump of the engine indicated generally at 57. Pump 57 is illustrated as located in the oil sump 68 of the engine, and is connected to said bellows, by a flexible conduit 58, a T connection 59 and a tube 61, whereby operation of the pump 15 by the engine causes the bellows 55 to be expanded to move the opening 54 in the latch 49 into registry with the reduced extension 52 of the push link 8. The push link is thus free to be moved by the accelerator pedal 1 to actuate the engine throttle without operating the starting mechanism so long as the engine is self-operating.

In order to prevent the actuation of the bellows 55 during the cranking operation, a valve 62 is provided on the cylinder 56, having an operating arm 63 connected by a link 64 to a stationary support 65. It will thus be seen that motion of the sleeve member 18 to close the starting switch will cause the valve 62 to be closed whereby the oil pressure is cut off from the bellows 55 during cranking of the engine.

It will be noted that the oil pump 57, since it is operated by a cam 66 on a rotating shaft 67 of the engine, is equally effective whether the engine 25 is rotating in its normal direction or is rotated in a reverse direction due to backfire or other causes.

In order to allow the reestablishment of the starting connection a predetermined time after the engine has come to rest, means are provided 40 for dissipating the oil pressure such as an adjustable bleeder valve 68 which is set so that the oil pressure will be relieved to allow the reactivation of the starting mechanism after a predetermined lapse of time. 45

Although certain embodiments of the invention have been shown and described in detail, it will be understood that various other embodiments are possible and that changes may be made in the arrangements and proportions of the parts without departing from the spirit of the invention as defined in the claims appended hereto.

What is claimed is:—

1. In combination, starting mechanism for internal combustion engines including a starting switch, a manual control member, a connection for operating said starting switch from the manual member, an engine driven fluid pressure pump, means responsive to pressure caused thereby for disabling said connection and means for preventing the operation of said disabling means during the cranking operation.

2. In combination, starting mechanism for internal combustion engines including a starting switch, a manual control member, a connection 65 for operating said starting switch from the manual member, an engine driven fluid pressure pump, means responsive to pressure caused thereby for disabling said connection and means for preventing the restoration of said connection for a predetermined time after operation of the pump has ceased. 70

3. In combination, starting mechanisms for internal combustion engines including a starting switch, a manual control member, a connection for 75

operating said starting switch from the manual member, an engine driven fluid pressure pump, means responsive to pressure caused thereby for disabling said connection, means for preventing the 5 operation of said disabling means during the cranking operation and means for preventing the restoration of such connection for a predetermined time after operation of the pump has ceased.

4. In combination, starting mechanism for internal combustion engines including a starting switch, a manual control member, a connection for operating said starting switch from the manual member including a movable latch member, an 5 engine driven pump, means responsive to pressure caused by said pump for tripping said latch, a valve for controlling the tripping action and means for moving the valve into position to prevent the tripping action when the connection is 10 moved to cause actuation of the starting mechanism.

5. In combination with an internal combustion engine, a starting system therefor including a starting switch, a manual control member for said

engine, a connection for operating said starting switch from said manual control member when the engine is not in operation, a fluid pressure pump, means for operating said pump by rotation of the engine in either direction, means responsive to pressure caused thereby for disabling said connection, and means for dissipating said pressure a predetermined time after operation of the pump ceases. 5

6. In combination with an internal combustion 10 engine, a starting system therefor including a starting switch, a manual control member for said engine, a connection for operating said starting switch from said manual control member when the engine is not in operation, a fluid pressure pump, 15 means for operating said pump by rotation of the engine in either direction, means responsive to pressure caused thereby for disabling said connection, and an adjustable bleeder valve for dissipating said pressure and allowing the reestablishment of said connection a predetermined time 20 after actuation of the engine ceases.
